CLAIM

The ornamental design for a case for filing papers, as shown and described.

DESCRIPTION

FIG. 1 is a front elevational view of a case for filing papers showing our new design;

FIG. 2 is a top plan view thereof;

FIG. 3 is a rear elevational view thereof;

FIG. 4 is a side elevational view thereof, the opposite side being a mirror image;

FIG. 5 is a perspective view of the case in an open position;

FIG. 6 is a perspective view of FIG. 5, with the clips removed; and,

FIG. 7 is a sectional view taken along line 7—7 of FIG. 2.

FIG. 1.

FIG. 2.

FIG. 3.

FIG. 4.

FIG. 5.

FIG. 6.

FIG. 7.
